UNITED STATES PATENT OFFICE.

FRANK GEORGE BAUM, OF SAN FRANCISCO, CALIFORNIA.

HIGH-TENSION INSULATOR.

No. 838,163.

Specification of Letters Patent.

Patented Dec. 11, 1906.

Application filed October 24, 1905. Serial No. 284,184.

To all whom it may concern:

Be it known that I, FRANK GEORGE BAUM, a citizen of the United States, residing at San Francisco, in the county of San Francisco and State of California, have invented certain new and useful Improvements in High-Tension Insulators, of which the following is a full, clear, and exact description.

My invention relates to high-tension insulators. In long-distance transmission of electric currents it is common to employ very high voltages in order to transmit the required power with a minimum size of line conductors. In the insulation of potentials of sixty thousand to one hundred thousand volts and over serious difficulties arise by reason of "leakage" or "creepage" of the electricity over the surface of the insulators. The leakage is due principally to dust and moisture upon the surface of the insulators, which constitutes a film for the conduction of electricity or minute conducting areas between which static discharges may take place. In order to absolutely prevent leakage across the surface of the insulator, it is necessary that the latter be perfectly clean and dry and have sufficient intervening surface between the conductor and its supporting means.

In order to secure a dry surface, insulators are commonly made with several "petticoats," so as to present a minimum unprotected surface to the atmosphere to gather dust and damp. In time, however, even the protected surfaces are liable to become covered with a deposit of dust, which greatly impairs the insulation, and since the surfaces are not exposed they are not washed off by the rains under these conditions.

The object of my invention is to provide an insulator which shall be capable of resisting very high voltages, which shall operate efficiently in rainy weather, and which shall not be liable to deterioration from accumulations of dust upon its surface.

A further object of my invention is to provide an insulator which shall be of simple, strong, and compact construction and which is adapted to use with the existing posts and supporting-pins.

With these and other objects in view my invention consists in the construction, combination, location, and arrangement of parts, all as will be more fully hereinafter set forth, 55 as shown in the accompanying drawing, and

finally particularly pointed out in the appended claims.

The drawing shows an insulator embodying the principles of my invention, partly in section and partly in side elevation.

It will be understood that surfaces which are exposed to the weather to a sufficient extent to be effectually washed off by the rains are in position to have their insulation impaired during the storm by the coating of moisture. In carrying out my invention I make use of the combination of weather-washed surfaces with petticoat-protected surfaces.

Referring to the drawing, in which like parts are designated by the same reference-sign, 1 indicates a petticoated insulator of substantially the ordinary form, having petticoats 2, 3, 4, and 5 thereon, each of which has its interior surface ribbed or corrugated, so as to provide a greater insulating-surface.

6 indicates the usual cement fillings by which the different petticoats are secured together.

The upper petticoat 5 is provided with the usual annular groove 7 for the reception of any clamping or securing devices. I make use of this groove 7 for supporting a supplemental and weather-washed insulating member, which constitutes an essential feature of my invention. I have illustrated a practical form of this supplemental insulator comprising an insulating-tube 8, of porcelain or other material, having annular ribs 9 extending along a considerable distance at each end thereof. The central portion of the tube is conveniently left smooth, as at 10, and fits in the groove 11 on the petticoat 5.

12 indicates supporting-straps by which the tube 8 is secured to the body of the insulator 1. In the drawing these straps comprise stamped metal plates, which are slightly bent to surround the tube 8 and the groove 7 and are clamped into place thereon by clamping-bolts 13. The particular method of supporting the tube 8 from the insulator 1 is not important, it being merely essential to secure the two together so as to leave the ribbed ends 9 exposed and out of contact with the main insulator.

The supplemental insulator 8 is provided with means for holding the line-wire in place, and I have shown the supplemental insulator as having a longitudinal square hole 14 with slightly flared ends. Within this hole I in-

sert a supporting-frame of metal rod 15, which may be held in place by a layer of cement 16 at its central portion. The ends 15' of the supporting-frame are afterward bent upwardly and toward one another, so as to form alined sections 15', to which the line-wire may be conveniently attached. 17, indicates the line-wire, which is strapped to the frame 15 by binding-wire 18. This form of supporting-frame may of course be widely modified and still embody the principles of my invention, so I do not desire to be limited or restricted to the form shown.

By virtue of the above arrangement the insulation strain lies between the cement 16 and through the body of the insulators 8, 5, 4, 3, and 2, which is almost an absolute insulation for practical purposes. Surface leakage may only take place along the interior walls of the supplemental insulator 8, over the entire area formed by the exterior ribs 9, and finally over all of the successive exterior and interior surfaces of the quadruple petticoated main insulator 1. In this action it will be observed that the leakage must always traverse an extensive weather-washed surface—namely, the ribs 9—and an extensive protected surface—namely, the interior ribbed faces of the quadruple petticoats 2, 3, 4, and 5. The ribs 9 being washed by the rains are always absolutely clean and secure perfect insulation in dry weather. In wet weather the interior surfaces of the petticoats 2, 3, 4, and 5 are in condition to effectively insulate the current.

Having described my invention, I claim—

1. In a high-potential insulator, a main insulating member having petticoats, and a supplemental insulator having a surface adapted to be washed by the rains, both of said insulators being arranged to be traversed in series by the leakage currents from one of the circuit-wires to another of the same circuit.

2. In a high-potential insulator, a main insulating member having petticoats with internal ribs thereon, and a supplemental insulator having ribs thereon, adapted to be washed by the rains, the two insulators being in series to oppose leakage currents from one circuit-wire to another of the same electrical circuit.

3. In a high-potential insulator, an insulating member having petticoats, a tubular

integral supplemental insulator secured thereto, and means on said supplemental insulator for the attachment of a line-wire. 55

4. In a high-potential insulator, a main insulating member having petticoats, a tubular supplemental insulator secured thereto, 60 and a line-wire-attaching frame extending through said tubular insulator.

5. In a high-potential insulator, a main insulator having a petticoat with an annular groove, a supplemental tubular insulator 65 having its surface exposed to the rains, and means surrounding said groove for attaching said supplemental insulator to the main insulator.

6. In a high-potential insulator, a main insulator having a petticoat, a supplemental tubular insulator having ribbed ends and attached to said petticoat at its central portion, and a line-wire-carrying frame extending through said tubular insulator. 70

7. In a high-potential insulator, a main insulating member having a petticoat, a supplemental insulating-tube secured to the top of said petticoat at the central portion of said tube, annular ribs upon the ends of said tube, 80 and a line-wire-carrying frame extending through said tube and supported thereby. 75

8. In a high-potential insulator, a main insulating member having a petticoat, a tubular insulator supported from the top of said petticoat and having projecting end portions exposed to the weather, and a line-wire supported by said tube whereby an insulation strain is imposed over the weather-washed surface thereof. 90

9. In a high-potential insulator, a main insulator having a petticoat, and integral tubular insulator having projecting ribbed ends and secured to said petticoat, and a line-wire supported by said tubular insulator. 95

10. In a high-potential insulator, a main insulating member having a vertical axis, and a supplemental integral tubular insulator horizontally disposed upon said main insulator and having vertical ribs or corrugations exposed to the weather. 100

In witness whereof I subscribe my signature in the presence of two witnesses.

FRANK GEORGE BAUM.
